(57) **CLAIM**

The ornamental design for a dental connector, as shown and described.

DESCRIPTION

FIG. 1 is a front view of a dental connector, showing our new design;

FIG. 2 is a rear view of FIG. 1;

FIG. 3 is a left side view of FIG. 1;

FIG. 4 is a right side view of FIG. 1;

FIG. 5 is a bottom view of FIG. 1;

FIG. 6 is a top view of FIG. 1;

FIG. 7 is a perspective view of FIG. 1; and,

FIG. 8 is a cross-sectional view of the dental connector. The claimed design is shown in solid lines in the drawings. The separations depicted by the break lines indicate an indeterminate length. Any portion of the article between the break lines forms no part of the claimed design.

1 Claim, 8 Drawing Sheets(56)
